OLEOMARGARINE SPREADER FOR AN EAR OF CORN

Warren Grown, 10945 Victory Blvd.,
North Hollywood, Calif. 91606

Filed Oct. 2, 1968, Ser. No. 13,816

Term of patent 14 years

Int. Cl. D7—99

U.S. Cl. D44—29

FIG. 1 is a side elevational view of an oleomargarine spreader for an ear of corn, showing my new design;

FIG. 2 is a top plan view;

FIG. 3 is a bottom plan view;

FIG. 4 is a right end elevational view;

FIG. 5 is a left end elevational view; and

FIG. 6 is a sectional view on line 6—6 of FIG. 1.

I claim:

The ornamental design for an oleomargarine spreader for an ear of corn, as shown.
